CLAIM

The ornamental design for a cooling device for electronic device, as shown and described.

DESCRIPTION

This application is related to commonly assigned, co-filed U.S. Utility patent application Ser. No. 14/833,399, by petitioner and entitled “Cooling Device for Electronic Device,” which is hereby incorporated herein by reference in its entirety.

FIG. 1 is a front perspective view of a cooling device for electronic device comprising the new design;

FIG. 2 is an enlarged view of a section of the design as indicated in FIG. 1;

FIG. 3 is a front view of the design of FIG. 1;

FIG. 4 is a back view of the design of FIG. 1;

FIG. 5 is an enlarged cross-sectional view of a portion of the design of FIG. 1 as indicated in FIG. 4;

FIG. 6 is a left view of the design of FIG. 1;

FIG. 7 is a right view of the design of FIG. 1;

FIG. 8 is a bottom view of the design of FIG. 1; and,

FIG. 9 is a top view of the design of FIG. 1.

The broken lines shown in the figures represent environment only and form no part of the claimed design.
